Primary Examiner — Michelle E. Wilson*Assistant Examiner* — Clese Moore, Jr.*(74) Attorney, Agent, or Firm* — Kirk A. Buhler; Buhler & Associates(57) **CLAIM**

The ornamental design for a weighted collection mat as shown and described.

DESCRIPTION

FIG. 1 is a top perspective view for a weighted collection mat showing my new design;

FIG. 2 is a left side view thereof;

FIG. 3 is a right-side view thereof;

FIG. 4 is a front side view thereof;

FIG. 5 is a rear side view thereof;

FIG. 6 is a top side view thereof; and,

FIG. 7 is a bottom side view thereof.

The even-length broken lines within FIGS. 1, 6 and 7 represent stitching and form no part of the claimed design. The claimed design is shown with a symbolic break in its length. The appearance of any portion of the article between the break lines forms no part of the claimed design.

The broken lines of the buckle components in FIGS. 1-7 forms no part of the claimed design.

1 Claim, 3 Drawing Sheets---
